J. R. CARDWELL.

RAILWAY CAR.

APPLICATION FILED MAR. 20, 1911.

1,106,129.

Patented Aug. 4, 1914.

UNITED STATES PATENT OFFICE.

JAMES R. CARDWELL, OF CHICAGO, ILLINOIS, ASSIGNOR TO UNION DRAFT GEAR COMPANY, OF CHICAGO, ILLINOIS, A CORPORATION OF ILLINOIS.

RAILWAY-CAR.

1,106,129.

Specification of Letters Patent.

Patented Aug. 4, 1914.

Application filed March 20, 1911. Serial No. 615,753.

To all whom it may concern:

Be it known that I, JAMES R. CARDWELL, a citizen of the United States, and resident of Chicago, county of Cook, and State of Illinois, have invented certain new and useful Improvements in Railway-Cars, of which the following is a specification, and which are illustrated in the accompanying drawings, forming a part thereof.

10 The invention relates to improvements in railway cars, and has particular reference to the application thereto of draft and buffering mechanism.

The object of the invention is to increase 15 the efficiency of devices of this character; and it consists broadly in so constructing the car and the draft and buffering mechanism thereof that the draft appliance is housed between the end of the car and the transom 20 or body bolster, and, while serving in part as the buffering device, is supplemented as such by buffering mechanism located back of the transom and connected with the draft mechanism by means of a plunger or thrust 25 bar which passes beyond the transom.

The invention is capable of embodiment in various known types of cars, there being used, for the purpose of disclosing its character, a common form of friction draft 30 mechanism.

In the accompanying drawings, Figure 1 is a detail plan of a railway car with the flooring removed, the draft sills being shown partly in section; and Fig. 2 is a detail longitudinal section of the car, the draft and buffering mechanisms being shown partly in section and partly in elevation.

The end sill of a car is shown at 10; its draft sills at 11, 12, and one of its transoms 40 or bolsters at 13. The coupler is shown at 14, and is provided with the usual tail-strap or yoke 15 which encircles the followers 16, 17. The forward follower engages a pair of draft lugs 18, 19, which are secured to the 45 inner faces of the sills 11, 12. Between the followers 16 and 17 there is located any suitable form of yielding pressure-absorbing devices; as shown, such devices comprising two pairs of triangular wedge-blocks 20, 21, 50 and 22, 23, seated, respectively, against the adjacent faces of the followers 16, 17; a block 24, having oblique or wedging faces at each end for engaging the adjacent faces of each pair of the first-mentioned blocks; a 55 pair of beveled plates 25, 26, bearing against

the outer faces of the members of each pair of the first-named wedge-blocks; a bolt 27 extending transversely through the members 24, 25 and 26, and carrying upon each of its ends coiled springs 28, 29, which react between abutments 30, 31, adjacent the ends of the bar 13, and abutments 32, 33, sleeved upon the bar and bearing, respectively, upon the members 25, 26. The draft gear described is of the form shown in Patent No. 65 819,266, granted to me May 1st, 1906.

A buffering appliance which may be and, as shown, is of the same character as the draft appliance, is located back of the transom or bolster 13 and comprises a forward and rearward follower 34, 35, the latter abutting against lugs 36, 37, secured to the sills 11, 12; triangular wedging blocks 38, 39, and 40, 41; a central wedging member 42 co-operating with both of such pairs of wedging 75 blocks; beveled plates 43, 44, engaging the outer faces of the several wedging blocks; the transverse bolt 45 passing through the members 42, 43, and 44; the springs 46, 47, carried by the bolt and reacting between 80 outer abutments 48, 49, and inner abutments 50, 51.

Interposed between the rearward follower 17 of the draft mechanism and forward follower 34 of the buffering mechanism just described is a plunger or thrust bar 52, which, in the construction shown, passes through a transverse aperture 53 in the transom or bolster 13. The forward end of the bar 52 may be supported upon brackets 54, 55, secured to the inner faces of the sills 11, 12, 90 and is bifurcated, as shown at 56, to straddle the rear end of the yoke 15 and to allow backward movement thereof.

Upon the application of pulling stresses 95 the follower 17 is drawn forward against the resistance of the springs 28, 29, and the various wedges co-operating therewith, the stresses being transmitted to the draft sills through the forward follower 16 and the 100 lugs 18, 19. Upon the application of buffering stresses the coupler 14 is moved inwardly and forces back the forward follower 16 against the resistance of the springs 28, 29, and the various wedges co-operating 105 therewith, the stresses being transmitted through the rearward follower 17 to the bar 52, and through this bar and the buffering mechanism to the draft sills. The buffering mechanism back of the transom may be, and 110

preferably is more powerful than the draft mechanism, and will not yield to the lighter pressures which are resisted entirely by the forward gear. After the draft gear has 5 been completely compressed the buffing gear will begin to yield.

It has been found impracticable heretofore, because of the contracted space between the end of the car and the transom or 10 body bolster, to provide buffing mechanism capable of resisting the severe stresses due to the violent impact of the cars incident to hasty or careless manipulation in making up trains, and especially due to the lighter 15 collisions. By the form of construction herein shown and described, the ordinary draft mechanism, which heretofore has been relied upon for dissipating the buffing stresses, may be supplemented by a buffing mecha-

nism having sufficient resistance to prevent 20 damage to the cars, even though the buffing stresses be much more severe than a draft mechanism can withstand.

I claim as my invention—

In combination, a car having a body 25 bolster, draft gear located between the end of the car and the bolster and comprising a follower, a coupler bar, and a yoke attached to the coupler bar and encircling the follower, buffing gear located back of the bolster, and a thrust bar interposed between the draft and buffing gears, the forward end of the thrust bar being bifurcated to inclose 30 the yoke.

JAMES R. CARDWELL.
